UNITED STATES PATENT OFFICE.

HARRY JOSEPH HICK, OF ALLIANCE, OHIO, ASSIGNOR TO THE MCCASKEY REGISTER COMPANY, (INCORPORATED IN 1914,) OF ALLIANCE, OHIO, A CORPORATION OF OHIO.

FILING APPLIANCE.

1,299,724.

Specification of Letters Patent.

Patented Apr. 8, 1919.

Application filed August 10, 1916. Serial No. 114,156.

To all whom it may concern:

Be it known that I, HARRY J. HICK, a citizen of the United States, residing at Alliance, in the county of Stark and State of Ohio, have invented certain new and useful Improvements in Filing Appliances, of which the following is a specification.

The invention relates to an appliance for filing sales-bills and other similar papers composed of a series of hinged holders, and a case in which the holders are operatively mounted and in which they can be completely inclosed for protection against fire and like damage; and the improvement comprises the use of a case or cabinet for the hinged holders, in the form of an ordinary upright fireproof safe in which the front wall may be composed of one or more laterally swinging doors.

One object of the invention is to utilize the available receiving chamber within the case or cabinet with a single set or series of hinged holders for filing the maximum number of bills therein; and in carrying out this object the foremost holder is pivotally mounted on a rocking support upon the forward end of a movable carriage with a counterbalance arm extending under the hinged ends of the rearmost holder, and an oscillating follower frame is also mounted upon the carriage for supporting the rearmost holder in upright position.

The object of the invention, and other ancillary advantages, are attained by the construction, arrangement and mechanism illustrated in the accompanying drawings, forming part hereof, in which—

Figure 1 is a vertical section of the case with the door opened and broken away, showing, in side elevation, the series of hinged bill holders in normal upright position within the case, and showing the track table and its leg section swung upward within the door opening in front of the holders;

Fig. 2, a similar section of the case with the bill holders moved forward into operative position, showing in full lines, the normal upright position of the holders, and showing, in broken lines, the reclined position thereof;

Fig. 3, a fragmentary side elevation showing the case in section, and illustrating the operation of the bill holders;

Fig. 4, a fragmentary plan view showing the case in section and the bill holders in normal upright position moved forward into operative position;

Fig. 5, a fragmentary perspective view, with certain parts dissociated, showing the method of mounting the foremost holder upon the wheel carriage;

Fig. 6, a fragmentary vertical section through the axis of one of the forward wheels;

Fig. 7, a similar section through the axis of the foremost bill holder; and

Fig. 8, a fragmentary perspective view showing one of the supporting rollers on the follower frame.

Similar numerals refer to similar parts throughout the drawings.

The case 1 of the filing appliance may be made of any well known fireproof construction, with spaced wall plates and intervening heat resisting material, and is preferably closed in front by the laterally swinging doors 2 in accordance with well known safe construction, so that the case can be opened in front the entire height and width of its receiving chamber 3.

The track table 4 is hinged at 5 to the bottom of the case inside the doors 2, and is adapted to be swung into upright position within the doors, as shown in Fig. 1, or to be swung into reclined position to form a table for the bill holders 6, when the same are drawn forward into operative position, as shown in Figs. 2, 3 and 4.

The leg section 4^a of the table is preferably hinged to the lower portion thereof, and is adapted to be folded under the same when in reclined position; and this section is provided with the brackets 7, forming supporting legs for the table when in reclined position; which legs are adapted to protrude within the receiving chamber of the case when the table 4 and its leg section 4^a are both rotated upward on the hinges, as shown in Fig. 1.

Track bars 8 and 8^a, in the form of plates secured on edge, are provided, one on each side of the bottom of the case, and one on each side of the table 4; upon the upper edges of which track bars, the carriage wheels 9 are adapted to travel.

The carriage frame is composed of the side plates 10, the rear ends of which are con-

nected by the yoke plate 11, and the forward ends of which are connected by the cross bar 12 which forms a handle by which the carriage can be moved by the operator.

5 The interval between the forward ends of the track bars 8 and the rear ends of the track bars 8^a, when the track table is swung downward into reclined position, are preferably bridged by the links 13 mounted on the 10 pins 13^a and 13^b on the inner sides of the respective track bars; upon which links the flanges 9^b of the carriage wheels are adapted to travel across said interval. And the cross bar 14 is preferably provided at the free end 15 of the track table, which serves as a handle for swinging the same, and also serves as a support for the bill holders when reclined upon the table, as shown in Fig. 3.

The rear pair of wheels 9 are journalled on 20 pintles 15 secured directly to the side plates 10 of the carriage frame, but the forward pair of carriage wheels 9^a, are journalled on pintles 16 extending laterally from the rearwardly extending link plates 17 which are 25 formed on the ends of the transverse floating bar 18 located under the forward end of the carriage frame.

The forward ends of each link plate 17 is 30 provided with the bearing aperture 19, the forward ends of each carriage side plate 10 is provided with the bearing aperture 20, and the hinged end of the foremost bill holder 6^a is provided with the bearing aperture 21; by means of which bearing apertures, these parts are all pivotally mounted upon the transverse pivot rod 22 extending transversely through the same, which pivot rod is provided with suitable cotter pins 23, washers 24 and spacing thimbles 25, for laterally securing and spacing the parts pivoted thereon.

The normal lower ends of the bill holders 6 are connected together by hinges 26, and when the holders are all rotated into upright position, some of the rearmost holders rest upon and are supported by the rearwardly extending counterbalance arms 27 as shown in Fig. 1, which are rigidly secured at their forward ends to the transverse floating bar 18; and it is evident that the link plates 17, the floating bar 18, and the counterbalance arms 27, constitute a rocking frame for supporting the bill holders.

By this construction and arrangement it 55 is evident that the weight of the bill holders 6 is carried primarily upon the pivot rod 22 which bears the foremost holder, and upon the forward ends of the link plate 17 on the ends of the floating bars 18; and that this 60 weight is ultimately borne by the forward set of carriage wheels 9^a which are mounted on the pintles 16 which are journalled in the rear ends of the link plate 17.

And it is evident that the weight of the 65 hinged holders 6 which is carried by the

foremost holder upon the pivot rod 22, which is located in front of the axis of the forward wheels 9^a of the carriage, tends to depress the forward end of the carriage and forward ends of the link plates 17, excepting only as 70 the same is counterbalanced by the weight of the rearmost holders when resting upon the counterbalance arms 27, which extend a greater distance in rear of the axis of the forward wheels 9^a than the pivot rod 22 is 75 located in front thereof.

For the purpose of stopping the depression of the forward end of the rocking frame when a considerable number of the foremost holders are rotated into reclined position, as 80 shown in Fig. 3, the stop post 28 is provided on the side plates 10 of the carriage frame at a point intermediate the axis of the forward carriage wheels and the pivot bar 22, which posts impinge the upper edges 85 of the link plates 17 and stop a further depression of the floating bar 18 when a sufficient number of holders 6 have been rotated into reclined position to raise the hinged ends of the rearmost holders from a bearing 90 upon the counterbalance arms 27, as shown in Fig. 3.

The parts are so proportioned and arranged that the stop posts 28 will prevent a further depression of the floating bar 18, 95 thereby stopping a further elevation of the rear ends of the counterbalance arms 27 when something less than half of the foremost bill holders have been rotated forward into reclined position; so that the counterbalancing action of these arms is not brought into play unless and until more than half of the bill holders have been rotated into upright position, after which the weight of the rearmost holders is carried by the counterbalance arms to such an extent that they will 100 not cause a slamming of the foremost leaves when they are started upward from reclined position.

A follower frame for supporting the rearmost holder in upright position is composed of the side bars 29 which are connected together at the rear ends by the yoke bar 29^a, and the side bars of this frame are pivotally mounted on each side to the pair of upright parallel links 30 and 30^a, the lower ends of the rear links being pivoted directly to the side plates 10 of the carriage frame, and the lower ends of the forward links being pivoted on the pintles 16 of the forward 110 carriage wheels 9^a.

A guide plate 31 is secured to and depends from each side bar of the follower frame, in which plate is provided the upright slot 32 in which the guide post 33 protruding from the hinged end of the rearmost holder 6^a operates to oscillate the follower frame forward and rearward as the foremost bill holders are rotated to and from reclined position. Suitable rollers 34 are pivoted at 125 130

the inner side of the rear end of each side bar 29 of the follower frame, against which rollers the rearmost frame rests and slides upward and downward during the operation of the 5 foremost holders.

The lower end of the guide slot 32 is preferably inclined rearward and may be formed on a curve substantially concentric with the pivot rod 22 of the foremost holder, so that the follower frame is not moved forward 10 very far until after quite a number of the foremost holders have been rotated into reclined position.

The bill holders are normally located in 15 upright position upon the carriage within the receiving chamber of the case, as shown in Fig. 1. For use of the appliance in filing or removing bills from the holders, track table 4 and its leg section 4^a are swung forward and the track section 4^a is folded under 20 and supports the table in reclined position, as shown in Fig. 2; after which the operator draws the carriage forward upon the track table until the forward wheels 9^a enter and 25 rest in the recesses 35 provided in the upper edges of the track bars 8^a, the shoulders of which recesses serve to stop the carriage with the bill holders thereon in operative position 30 in the front of the case, as shown in full lines in Fig. 2.

With the bill holders in this position, they are readily operated from their normal upright position, either singly or collectively, to and from the reclined position, shown by 35 broken lines in the same figure; in which reclined position, the foremost holder may rest upon the cross bar 14 at the forward end of the table.

As the weight of the hinged ends of a 40 number of the foremost holders is brought to bear directly upon the pivot rod 22 forming the fulcrum for the foremost holder, the forward ends of the carriage and of the link plates are depressed and the rear ends of the 45 counterbalance arms are raised by reason of the gradually lightened load thereon, until after half or more of the bill holders have been rotated forward, when a further depression of the forward end of the carriage 50 is stopped by the stop posts 28 striking the upper edge of the link plates 17 as shown in Fig. 3, after which the operation of the remaining rear holders is performed without the assistance of the counterbalance 55 arms.

In the operation of the appliance, the support given to the rearmost holders by the counterbalance arms when more than half

the holders are in upright position, serves to relieve the follower support from the 60 weight of the same.

I claim:

1. A filing appliance including a series of 65 holders hinged to swing from upright to reclined position, a yielding support including a floating bar with link plates on its ends, a pivotal support for the rear ends of the link plates, a pivotal connection between the forward ends of the link plates and the hinged end of the foremost holder, 70 and a counterbalance arm extending rearward from the floating bar under the hinged ends of the rearmost holders.

2. A filing appliance including a series of 75 holders hinged to swing from upright to reclined position, a yielding support including a floating bar with link plates on its ends, a pivotal support for the rear ends of the link plates, a pivotal connection between the forward ends of the link plates and the 80 hinged end of the foremost holder, and a counterbalance arm extending rearward from the floating bar under the hinged ends of the rearmost holders, with means for stopping depression of the yielding support. 85

3. A filing appliance including a series of 90 holders hinged to swing from upright to reclined position, a yielding support including a floating bar with link plates on its ends, a pivotal support for the rear ends 95 of the link plates, a pivotal connection between the forward ends of the link plates and the hinged end of the foremost holder, a counterbalance arm extending rearward from the floating bar under the hinged ends of the rearmost holders, a supporting follower for the rearmost holder, and means actuated by the operation of the holders for controlling the movement of the follower.

4. A filing appliance including a series of 100 holders hinged to swing from upright to reclined position, a yielding support including a floating bar with link plates on its ends, a pivotal support for the rear ends of the link plates, a pivotal connection between the forward ends of the link plates and the hinged end of the foremost holder, a counterbalance arm extending rearward from the floating bar under the hinged ends of the rearmost 105 holders, means for stopping depression of the yielding support, a supporting follower for the rearmost holder, and means actuated by the operation of the holders for controlling the movement of the follower. 110

HARRY JOSEPH HICK.
